VALVE GRINDER

Filed April 23, 1921

INVENTOR.
EARL G. SMITH.
By C. B. Burkenbush.
ATTORNEY.

UNITED STATES PATENT OFFICE.

EARL G. SMITH, OF PORTLAND, OREGON, ASSIGNOR OF ONE-HALF TO ALBERT B. COMBS, OF PORTLAND, OREGON.

VALVE GRINDER.

Application filed April 23, 1921. Serial No. 463,902.

To all whom it may concern:

Be it hereby known that I, EARL G. SMITH, citizen of the United States, and resident of Portland, in the county of Multnomah and State of Oregon, have invented a new and useful Valve Grinder, of which the following is a specification.

This invention relates more particularly to a device for grinding in the poppet valves of an internal combustion engine.

The object of my invention is to provide an exceedingly simple and efficient mechanism for grinding valves by applying a rotary movement back and forth, and at one of the reversals of rotation of said valve to permit same to rise off of its seat before again applying rotary motion, for the purpose of producing what is known as a satin finish on the valve and seat in preference to the bright finish produced when the valve is rotated in one or both directions without permitting same to be lifted manually, and to eliminate thereby the tendency of the abrasive to score the parts instead of producing a perfectly smooth and uniform surface.

I attain these results in the manner set forth in the following specification and illustrated in the accompanying drawing, in which:

Figure 1 is a vertical section through the device. Figure 2 is an end elevation. Figure 3 is a horizontal section along the line 3-3 in Fig. 1. Figure 4 is a detailed view of the valve. Figure 5 is a section along the line 5-5 in Fig. 4. Figure 6 is a section along the line 6-6 in Fig. 4. Figure 7 is a partial plan of the valve casing showing a modification of the manner of forming a narrow port or passageway partially around the perimeter of the valve. Figure 8 is a sectional view along the line 8-8 in Fig. 7.

Similar numbers of reference refer to the same or similar parts throughout the several views.

Referring in detail to the drawing, I have constructed my device of a frame 10 in which is formed a cylinder 11 whose upper end is sealed by means of a threaded plug 12 to which is secured a handle 13 which is used in operating the device. Within the cylinder 11 I have placed a piston 14 which is held against rotation by means of the spline 15 which lies in a spline-way 16 in

the piston 14. A screw 17 provided with a jamb nut 18 holds the spline 15 in place.

The piston 14 is provided with a central opening 19 throughout almost its entire length, the upper end of the piston 14 being closed and the lower end being counter-bored to receive a perforated disk 20, which is pinned to the piston 14 to prevent rotation and held in place by means of the circular nut 21. Slidably supported in the somewhat square perforation in the disk 20 is a spiral-ended shaft 22 capable of rotation but not of sliding movement. It receives a backward and forward rotation from the reciprocating movement of the piston 14.

The lower end of the cylinder 11 is closed by means of the threaded plug 23 which forms a journal for the shaft 22 and is provided with a suitable stuffing-box 24. This shaft 22 is secured to the flanged sleeve 25 by the pin 26. The shaft 22, however, does not project through the full length of the sleeve 25 but permits the insertion of a shank 27 to which it may be secured by a pin 28.

On the flange 29 of the sleeve 25 I have mounted the two wrist pins 30 on each of which is pivoted a plunger 31, and around which is placed a spiral compression spring 32.

In the frame 10 and parallel to the axis of the cylinder 11 I have placed a rotary valve 33 having a shouldered head 34 which may be knurled to assist in the manual operation of the valve, if desired. A hole 35 is formed in the valve 33 from its upper end and extending almost its entire length. Connecting the bottom of this hole with the exterior of the valve is a port 36 which is arranged to register with the port 37 in the wall of the valve chamber and communicating with the lower end of the cylinder 11 when the valve 32 is in one of its extreme positions. A second port 38 connects the upper end of the hole 35 with the upper end of the cylinder 11 when it registers with the communicating port 39 at the opposite extreme position of travel of the valve 33. The opening 40 passes entirely through the valve 33 and a balancing groove 41 is turned around the valve at the hole 40. Suitably controlled air pressure is admitted through an air hose to the nipple 42 which is threaded into the valve casing 43. A self-closing oiling plug 105

44 is threaded into the upper end of the hole 35 in the valve 33.

The lower end 46 of the valve 33 is shoudered and has secured thereon by means of the pin 47 a disk 48 which is recessed on one side to form the two stop faces 49 which are adapted to engage the screw 50 and limit the travel of the valve in either direction.

A square-faced notch 51 is also formed in the periphery of the disk 48. A pair of pawls 52 are mounted on the stud 53 on which they are secured by means of the cotter 54. A double-ended spring 55 is also mounted on the stud 53 between the pawls 52 and holds same against the periphery of the disk 48. The notch 51 and the spacing of the pawl tips are proportioned to permit one or the other of the pawls to engage one of the square faces of the notch 51 in either of the extreme positions of the valve 33, thereby locking same in place against the stop 50. Also on the disk 48 are the two pivotal guides 56 which receive the ends of the plungers 31. Extension sleeves 57 are secured to the guides 56 to prevent the plungers 31 from escaping from their guides in certain positions which will develop through the operation of the machine.

It will be seen in Figure 3 that the tip 58 of either of the plungers 31 may engage its respective pawl whenever the member 29 approaches its extreme position in either direction. As an illustration in this figure it will be seen that in assuming this position the plunger 31 first compresses the spring 32 until the point 58 of the plunger 31 presses against the pawl 52 and disengages it from the notch 51. It will be borne in mind that the locked position of the valve represents the time during which the inlet and outlet valves are wide open. The instant that the pawl 52 is released the valve 33 is quickly rotated to its opposite position and a corresponding condition prevails.

Near the ports 36 and 38 I have provided the longitudinal grooves 59 which are adapted to connect with the exhaust ports 60 formed in the side of the valve chamber 43. The exhaust ports 60 are placed a safe distance away from the ports 36 and 38. Circular grooves 59^A connect with the grooves 59 in order to complete the passageway to the exhaust ports 60.

In order to protect the working parts of the valve operating gear I have provided an easily removable cover 61 which is held in place by means of the screw 50.

Inasmuch as the various valves are chiefly equipped with slots and holes for turning same I have supplied a special tip 62 having standard shapes formed on its various sides which may be brought into use by extracting the pin 63 and turning the desired shape downward and then reinserting the pin 63.

In Figures 7 and 8 I have illustrated a

simple method for accomplishing the same results produced by the grooves 59^A. A hole 59^B is drilled through the valve casing 43 at the same height as the groove 59^A so that it will break into the valve chamber as illustrated. This hole, of course, would then be plugged in the most convenient manner, preferably by the use of a screw 59^C.

The operation of my device is as follows: After placing a suitable abrasive between the valve and its seat and engaging the member 62 with the valve, air is admitted to the interior of the valve 33. If for any reason the valve 33 has stopped on center it must be brought to either of its extreme positions manually by means of the knurled head on the cap 34. Air is then admitted to the cylinder 11 and the piston 14 is forced to its opposite end, which in turn, causes a vertical rotation of the shank 27 and therefore of the valve being reseated. The reversal of the valve 33 being accomplished as previously described causes the piston 14 to return to the opposite end of the cylinder, which reversal of motion causes a slight jump to the mechanism which is followed by the valve being raised due to the action of the valve spring itself.

It is this jumping action which permits the admission of more abrasive and the shifting of its position with relation to the valve seat, and also produces what might be termed to be a riveting action on the metal of the valve and its seat, rather than a polishing or smoothing action previously referred to. It is this jumping action which produces the satin finish so desirable for the perfect seating of a valve.

While I have thus illustrated and described my invention it is not my purpose to limit myself to this precise form or method of application, but intend that it shall cover all forms and modifications that fall fairly within the appended claims.

What I claim as new is:

1. A valve grinder having in combination a body member including a cylinder formed therein, a slidable piston within said cylinder including means for holding same against rotation, a rocking shaft projecting into said piston and outside of said cylinder, said shaft having a square end formed into a spiral which fits into a square hole in said piston, a flanged tool-holding sleeve secured on the rounded end of said shaft, a rotary valve within said body member having ports for admitting air from its interior to the opposite ends of said cylinder alternately, a notched disk secured to said valve, a pair of pawls adapted to engage the notch in said disk at opposite ends of the valve travel, a pair of plungers pivoted on said flanged sleeve, guides on said disk adapted to direct said plungers against said pawls and springs on said plungers adapted to ro-

tate said valve after it is released by said plungers.

2. In a controlling mechanism for rotary valves, the combination of a rotatable valve, a fixed stop for limiting the rotation of said valve, a pair of opposed pawls engaging the periphery of said valve, means for releasing alternate pawls at each valve movement, and spring means for actuating said valve.

10 3. In a controlling mechanism for rotary valves, the combination of a rocking crank member having two opposed spring-carrying plungers pivoted to its face, a rotary valve mounted parallel to the axis of said 15 crank, a disk mounted on the end of said valve having a recess in its periphery, a stationary stop means mounted between the ends of said recess, said disk having a notch also formed in its periphery, a pair of opposed pawls mounted on a common pivot and adapted to engage said notch at either 20 end of its travel, a pair of opposed guide members pivoted on said disk in a manner to slidably receive the ends of said spring-carrying plungers and force same against 25 said pawls whenever their respective springs are sufficiently compressed.

4. The combination of a rocking crank member having mounted theron a pair of 30 wrist-pins with a pair of plungers pivoted on said pins, a notched valve actuating disk, a pair of pawls adapted to engage the notch

in said disk, a pair of guides for said plungers pivoted on said disk, said guides directing said plungers toward said pawls, 35 and springs on said plungers adapted to be compressed by said crank until said plungers disengage said pawls alternately which permits said compressed spring to rotate 40 said valve.

5. In a valve grinder, the combination of a body member including a rotary valve and a cylinder containing a slidable piston having means for holding same against rotation, a handle threaded into the upper end of said cylinder, a plug threaded into the lower end of said cylinder, a shaft journaling in said plug, said shaft having a spiral end extending up into said piston, a nut fitting said spiral secured to said piston 50 adapted to impart a rocking motion to said shaft as said piston is reciprocated, a flanged sleeve secured to the end of said shaft which projects from said plug, a pair of wrist pins mounted on said flanged sleeve, a pair of 55 plungers pivoted on said wrist pins, a notched disk secured on said valve, a pair of plunger guides rotatably carried by said disk, springs on said plungers between said wrist pins and guides and a pair of opposed 60 pawls adapted to engage the notch in said disk and to be disengaged by the first portion of the travel of said plungers.

EARL G. SMITH.
